UNITED STATES PATENT OFFICE.

HENRY F. MOELLER, OF DAVENPORT, IOWA.

DESIGN FOR A BOX.

SPECIFICATION forming part of Design No. 12,942, dated May 23, 1882.

Application filed April 13, 1882. Term of patent 14 years.

To all whom it may concern:

Be it known that I, HENRY F. MOELLER, of Davenport, in the county of Scott, and State of Iowa, have invented a Design for Boxes, of 5 which the following is a specification.

My design is intended for embodiment in or application to boxes for containing cigars; and it consists in a box made in the form of a book, bearing on its exterior the title, "Dr. Quack's 10 Medical Works," and on the inner face of the lid or cover a representation of a doctor's office, more or less in the nature of a burlesque or caricature.

In the accompanying illustrations of my design, Figure 1 shows the exterior, and Fig. 2 15 the interior, of the box.

A represents the box proper, made in the form of a book, and bearing the inscription B, "Dr. Quack's Medical Works."

C is the representation of a doctor's office, showing a man sitting at a desk before shelves containing books, bottles, and other articles common to a doctor's office, while at the top 20 of the shelves are represented curiosities of nature. A placard hanging over the edge of the desk bears the inscription, signed, "Dr. Quack,"—"A good Habana Cigar cures the blues in 5 minutes." At the end of the desk 25 a pot or vase of flowers partially hides a piece of statuary. Over the mantel, on which stand two statuettes and a clock are grouped Indian 30 reliques, and in the foreground stands a table

bearing a bottle and decanter, a box of cigars, and fruit, and a monkey seated on the table is represented as indulging in the luxuries before him, while a cat amuses itself playing with the monkey's tail, and a dog sits up and looks on with apparent interest in the performances of his companions. The title "Dr. Quack's Medical Works" is also placed on the 35 40 picture. The picture is usually printed in colors and pasted to the lid or cover. The purpose of the picture is to convey at once the idea of a doctor's office, and by its comical appearance and novelty to attract the attention of persons before whom the box is displayed. 45

Having thus described my design, what I claim is—

1. The herein-described design, consisting 50 of a box made in the form of a book, and bearing on the outside the inscription, "Dr. Quack's Medical Works," and on the inside a representation of a doctor's office, substantially as shown.

2. The representation of a doctor's office, 55 consisting of the figures and articles arranged substantially as shown, and constituting a picture for the ornamentation of boxes, as set forth and shown.

HENRY F. MOELLER.
